United States Patent Office.

C. C. HARE, OF KANSAS CITY, MISSOURI.

Letters Patent No. 90,259, dated May 18, 1869.

IMPROVED GAS-MACHINE.

The Schedule referred to in these Letters Patent and making part of the same.

To all whom it may concern:

Be it known that I, C. C. HARE, of Kansas City, in the county of Jackson, and State of Missouri, have invented a new and improved Pneumatic Gas-Machine, for the manufacture of gas from gasoline, or the lighter products of petroleum; and I hereby declare that the following is a full, clear, and exact description thereof, reference being had to the accompanying drawings, and to the letters of reference marked thereon.

My invention consists in the construction of a gas-machine which shall be cheaper and more simple than those heretofore in use, and thus to cheapen the production of gas, for, in one device, I combine a blower and an evaporator.

To enable others skilled in the art to make and use my invention, I will proceed to describe its construction and operation.

Figure 1, in the drawings, represents a vertical longitudinal section of the machine, and

Figure 2, a vertical cross-section of the same, taken through the line *ff*.

The lines A A A A represent the form and walls of a reservoir or vessel to contain the gasoline to be used in operating the machine; and this should be made of any suitable metal, and water and air-tight.

N is an inlet-pipe, by which the gasoline is introduced, and

O, a connecting-pipe, for the discharge of the gas as it is formed.

The letters B represent the outer case or shell of a revolving cylinder or drum, and

The letters C, the inner case or shell of the same.

The letters D indicate metallic partitions, which run around spirally between the inner and outer cases or shells of the cylinder B, and divide the intervening space into a corresponding number of compartments or grooves, like internal screw-threads.

The inner and outer cases, and the partitions, are made fast together, and water and air-tight, with the exception of the proper openings, which will be described.

The inner case and the partitions extend from the rear end of the cylinder only about two-thirds of the way to the front end, and the compartments may run, say, once around the cylinder in their course from one end to the other, and are open at each end, for the entrance and exit of fluids and gases.

The cylinder is also provided with a sleeve, I, which is firmly made fast to it; and the hollow in the sleeve opens into the interior of the cylinder.

The rear end of the inner space of the cylinder is tightly closed, while the other end is left open into the body of the cylinder.

This cylinder revolves upon a hollow shaft, E, which passes through the sleeve, which is in the centre of the front head of the cylinder, and thence through the centre of the rear head of the same, and then is fastened into the rear end of the large vessel, so as to be

stationary in it, the end of the shaft being closed air-tight.

In order to make an air-tight joint where the hollow shaft passes through the rear head of the cylinder, a washer, *a*, may be made fast on the hollow shaft, and another, *b*, likewise fast on the inner side of the head, as a bearing for that end of the cylinder; another, *c*, on the outside, by which the head may be held against the washer *a*, by means of the spiral spring *K*.

In revolving, the cylinder, by its sleeve I, forms a journal in the stuffing-box *L*, on the front end of the main vessel.

The hollow shaft E never revolves, and the pipes H and G, which are closely jointed into it, forming a siphon, the use of which will be hereinafter explained.

The hollow shaft E is open at the end, *m*, for the air, which passes along in it until it comes to the closed partition *p*, and then passes up the pipes F, and thence into the interior of the revolving cylinder.

The joint between the end, *m*, of the sleeve I and the hollow shaft E, is made air and water-tight by the stuffing-box M.

One-third, or less, of the length of the spiral compartments, marked *d*, should be loosely filled, at their rear or discharge-ends, with cotton, wool, or other fibrous and porous material, which is to perform the office of thoroughly subdividing the gasoline or other fluid used, in order that the air may be the better enabled to absorb its vapors.

The hollow shaft E should pass through the outer main vessel so much below its centre that the cylinder may approach very near its bottom, for two reasons: first, that the machine may make gas when only a small quantity of the gasoline is in the vessel; and, secondly, that there be room in the upper part of the vessel for a sort of reservoir for the naphthalized air discharged from the spiral compartments or worms; and I will add, that these compartments may be made irregular in form, so as to be much larger midway between the points of entrance and exit, and in that way their efficiency may be increased; or, the space between the inner and outer shells of the cylinder may be filled with metal tubes or pipes bent in the spiral form.

The cotton or other fibrous material in the exit-ends of the grooves may be held from discharge by small stays, *h h h*.

When the machine is in operation, the cylinder should be filled with gasoline up at least as high as the bottom of the interior space, but not higher than the top of it.

The cylinder may be revolved by means of a weight or spring, or any suitable attachment to the sleeve I.

The operation of the machine is substantially as follows:

A proper quantity of gasoline having been introduced into the cylinder, and the air admitted through the mouth of the hollow shaft E at *m*, fills all the space

in the interior which has not been filled with gasoline. The cylinder is then revolved. Each groove being filled with air, takes in a quantity of the fluid, which is driven around its circuit, the air being driven before it, and out at the exits, and then out at O, and the fluid, after being discharged, falling upon the bottom of the outer vessel. The fluid, being thus constantly discharged into the outer vessel, induces a pressure, which causes the fluid to rise in pipe H, thence into the hollow shaft E, and thence it flows down through the pipe G, and is discharged into the cylinder from whence it started, thus keeping it, by this siphon-like action, always filled; and the pressure is increased by the constant discharge of air also into the large vessels.

It will be observed that the operation of my machine effects a very thorough subdivision and exposure of the fluid to the air, and this affords the latter great facility in taking up and absorbing the combustible vapors of the gasoline or other fluid.

At every revolution of the cylinder, the walls of the apertures or grooves are coated with the fluid, and the cotton, wool, or other fibrous material, thoroughly saturated with it, and then follows the air, to take up its vapors.

The cylinder is revolved very slowly, so that there is but little wear and tear, or strain, upon the parts, and the machine is always ready for use, and the manufacture of gas by it is very cheap, while the light afforded by it is as good as or better than that afforded by the common coal-gas.

In the drawings, the dark arrows indicate the currents of liquids; the red arrows, that of air and gas.

What I claim as new, and desire to secure by Letters Patent, is—

1. The revolving screw-cylinder, with its sleeve I, when used in the construction of a pneumatic gas-machine, constructed substantially as and for the purpose described.

2. Partially filling the spiral grooves of the cylinder described with cotton, wool, or other porous or fibrous material, substantially in the manner and for the purpose described.

3. The hollow shaft E, with its arms G, H, and F, and stop p, when used in the construction of a pneumatic gas-machine, constructed substantially as and for the purpose described.

4. The described revolving cylinder, in combination with the described hollow shaft E and its parts, when used in the construction of a pneumatic gas-machine, when constructed and arranged substantially as and for the purpose described.

5. The outer vessel A A A A, with its stuffing-boxes L and M, in combination with the described revolving cylinder and its parts, and the described hollow shaft E and its component parts, when used in the construction of a pneumatic gas-machine, constructed and arranged substantially as described.

6. The friction-joint K, in combination with the described cylinder and its component parts, and the described outer vessel and its parts, and the described hollow shaft and its component parts, when used in the construction of a pneumatic gas-machine, constructed and arranged substantially as and for the purpose described.

C. C. HARE.
